Primary Examiner — Jennifer Rivard(74) *Attorney, Agent, or Firm* — Carter, DeLuca, Farrell & Schmidt, LLP(57) **CLAIM**

The ornamental design for a heated hair roller base, as shown and described.

DESCRIPTION

FIG. 1 is a perspective view of the heated hair roller base in accordance with the principles of the present disclosure; FIG. 2 is a first side elevation view of the heated hair roller base;

FIG. 3 is a second side elevation view of the heated hair roller base;

FIG. 4 is a third side elevation view of the heated hair roller base;

FIG. 5 is a fourth side elevation view of the heated hair roller base;

FIG. 6 is a top plan view of the heated hair roller base; and, FIG. 7 is a bottom plan view of the heated hair roller base. The broken lines illustrate portions of the heated hair roller base and form no part of the claimed design.
